UNITED STATES PATENT OFFICE.

PAUL DE CARSALADE DU PONT, OF PARIS, FRANCE, ASSIGNOR OF ONE-HALF TO GABRIEL ESCARRAS, OF PARIS, FRANCE.

TYPE-WRITING MACHINE.

1,006,060.

Specification of Letters Patent. Patented Oct. 17, 1911.

Application filed July 19, 1909. Serial No. 508,510.

To all whom it may concern:

Be it known that I, PAUL DE CARSALADE DU PONT, a citizen of the French Republic, and resident of Paris, France, have invented 5 certain new and useful Improvements in Type-Writing Machines, of which the following is a specification.

This invention relates to typewriting machines and more particularly to that type 10 of machines in which the carriage whereon the paper is held instead of being animated with a reciprocating rectilinear motion, consists of a cylinder which revolves around its axle in such a manner that the lines, instead 15 of following a rectilinear displacement of the carriage, develop along the cross section of said cylinder.

With the machines of known construction and of the same type, the platen or cylinder 20 is vertically disposed, and upon completion of its rotation, it is moved upwardly or downwardly to present the paper for beginning a new line of print. With machines of this type it is further necessary to provide 25 three complementary keys, of which one serves for causing the cylinder to complete its rotation for one line of print, the other for providing the required margin, and the third to longitudinally displace or 30 shift the cylinder for the beginning of a fresh line of print; one of the auxiliary keys serving at the same time for putting under tension the spring which determines the rotation of the cylinder.

According to this invention, the platen whereon the paper is held is arranged horizontally and perpendicular to the operator; there is only one finger-key required for 35 shifting the lines; the spring which causes the rotation of the cylinder is automatically put under tension when a fresh sheet of paper is inserted and it remains under tension as long as this paper is in the machine.

In the accompanying drawings the invention is illustrated.

Figure 1 represents diagrammatically the arrangement of the platen with regard to and in combination with a printing mechanism of any convenient type. Figs. 2 and 3 50 show in ground plan and side view the mechanism of the platen. Fig. 4 is an end view of the platen. Fig. 5 is a perspective view of the same. Fig. 6 is a detail. Fig. 7 represents a modification.

55 Referring to Fig. 1 of the accompanying

drawings, the cylinder or platen *a* whereon the paper is held, is horizontally mounted beneath the printing device; the axle *b* of said platen is disposed perpendicular to the operator. The platen *a* revolves around its axle *b* during the printing of a line, so that the types are printed upon the paper along a line which runs at right angle to the axle *b*. When the printing of one line is completed, the spring *d* moves the platen *a* endwise upon its axle *b* to present the paper for beginning a new line of print.

According to my invention the platen *a* is hollow and its bottom *e* which is at the end opposite the operator, has at its center 60 a pivot *f* which engages with a boring of a support *g*. A tube *h* is centrally fixed on the inner surface of the bottom plate *e*; this tube contains the long spiral spring *d* destined to cause the longitudinal displacement 65 of the platen and the free end of said tube is telescoped in a second tube *i* which is guided in a central boring of the front bottom plate *m* of the platen, said boring having an extension at its upper end in which a longitudinal ridge *k* of tube *i* is guided, which prevents the rotation of tube *i* with regard to the platen *a* which thus is drawn along with tube *i* if the same rotates. The axle 70 *b* of the platen is fixed centrally in the outer end of tube *i* and the toothed wheel *n* destined to revolve the platen is keyed upon said axle. Wheel *n* can be driven by any suitable mechanism; such for example as a spring, said toothed wheel being thrown in 75 and out of gear by means of one of the numerous devices which are actually used with typewriting machines for this purpose. As these devices are generally known and may be of any convenient construction, they have 80 neither been represented in the drawings nor are they particularly described and it is clearly to be understood that said driving mechanisms do not form part of the present invention. In the following description it 85 is supposed that the driving wheel *n* for the platen is animated by intermittent revolving motions and stopped intermittently sufficiently long to permit the printing of a 90 character.

The platen *a* has a longitudinal slot *o* which extends over its entire length and behind which there is mounted in the cylinder *a* an axle *p* which carries a blade *q* adapted to bear against the inner surface of cylinder 105 110

a under the influence of a draw-spring *r* which is arranged upon the outer surface of end plate *e* of the platen and fixed with its other end to the inner end of a lever *s* located in the cylinder and projecting with its other end *t* through the slot *o*. This device, for which there could be substituted any other device of known construction and serving for the same purpose, is destined to grip and hold the paper *u*. The paper sheet is inserted with its free edge into the slot *o*, the lever *t* having been previously lifted so that the edge of the paper can easily penetrate between the blade *q* and the inner surface of the platen. The part of the paper sheet *u* which is inserted through slot *o* forms the margin, which can be of any width. The remaining part of the sheet hangs loosely along the outer surface of the platen. There could be used any suitable device for holding the paper upon the platen in connection with the device hereinbefore described, such as for example, india-rubber strips, elastic rings or the like, but the use of such auxiliary devices is not obligatory. If the lever *t* is released after the insertion of the paper in the platen, blade *q* is pressed against the inner surface of the platen under the action of spring *r* whereby the paper sheet *u* is securely held in its position. The platen *a* is guided by means of guide rollers *v* whose axles are fixed on the frame of the machine and between which moves a removable ladder which is composed of two beams *w* and steps *y*, which is fixed at one end in the support *g* of the platen and which has at its other free end stops *x* destined to limit the travel of the platen. The distance between the steps *y* of the ladder determines the distance between the lines of print upon the paper. The ladder is fixed in support *g* in such a manner that it can be easily removed and replaced by another ladder if the distance between the lines of print has to be altered.

In connection with the ladder there are provided two gripping levers 2 and 3 (Fig. 5) which are keyed upon a shaft 4 which is parallel with the axle of the platen *a*, said gripping levers having each at its upper end a hook 5 which is hinged to the lever in such a manner that it stops the steps *y* of the ladder if the same moves in the direction of the arrow (Fig. 5) giving way under the pressure of said steps if the ladder moves in opposite direction. Upon the front end of shaft 4 a catch lever arm 6 is keyed. A toothed wheel 7 which is keyed upon shaft *b* meshes with a toothed wheel 8 which is of double the diameter of wheel 7 so that it revolves through one half revolution for every complete revolution of shaft *b*. Upon the rear surface of toothed wheel 8 two projecting ribs 10 and 11 are provided which

arm 6 is continuously in contact with one of said two ribs against which it is pressed by means of a spring 12. Owing to this arrangement the shaft 4 receives at each revolution of the platen *a* an oscillating motion 70 so that the gripping lever 2 or 3 as the case may be which maintained the step *y* of the ladder against the action of spring *d* releases its step *y* so that the platen *a* is longitudinally displaced in the direction of the arrow 75 under the action of spring *d* to be stopped again by the next step *y* coming in contact with the corresponding gripping lever.

If a fresh sheet of paper *u* has to be inserted before the platen *a* has arrived at the 80 end of its travel, the stopping action of the gripping levers 2, 3 has to be put out of action; with this object in view said gripping levers 2 and 3 are extended beyond their pivot and the extensions 13 are maintained apart the one from the other at the required distance by means of springs 14 arranged below the shaft 4, a cam 15 being arranged between said extensions so that if the hand knob 16 is turned, the ends 13 of 90 the gripping levers are moved away the one of the other and consequently the upper ends of said levers swing outward, so that the ladder can move in longitudinal direction without being stopped by the gripping 95 levers 2, 3.

The tube *i* is slightly longer than the maximal height of the paper sheets to be used and the circumference of cylinder *a* has to be equal to the greatest length of the lines 100 to be printed upon sheet *u*. If a fresh paper sheet is to be inserted, the platen *a* has to be in normal position so that the slot *o* is completely open. After the paper sheet has been inserted in the manner hereinbefore 105 described, the platen *a* is pushed back in the direction opposite to the arrow in Fig. 5 which can be easily done owing to the articulations of hooks 5 of the gripping levers. By this back-motion of the platen *a* 110 the spring *d* is automatically put under tension and remains under tension as long as the paper sheet remains in position upon the platen. Hereupon the slot *o* of the platen is brought either by hand or by means of 115 the space bar to stand opposite the printing point and the typewriting machine can be manipulated in the usual manner. The printing is accomplished by striking the finger keys causing the stepwise revolution 120 of wheel *n* for the space of one tooth so that the platen will revolve, after a character has been printed, for a quantity equal to one space. When the line is concluded, shaft 4 oscillates automatically and the 125 platen *a* moves forward to present the paper for the beginning of a new line and without requiring the operator to touch said platen.

There is required only one auxiliary finger key to conclude a line at any point of 130

the width of the sheet and which merely serves to suppress the mechanism destined to stop the escapement wheel n in order to permit that the platen completes rapidly its revolution.

With a machine of this type the insertion of a fresh sheet of paper after a certain time can be avoided as the rotation of the cylindrical platen a can be used for continually feeding an endless strip of paper 17 such for example as used in telegraphs (Fig. 7), said strip of paper 17 having the tendency to wind around an axle 18 which is under the influence of a spring, but owing to the two guide rollers 19 and 20 which press said strip upon the surface of the cylindrical platen, the strip can move only during the rotation of the platen. Thus, very long texts can be printed without 20 changing the paper, whereby the speed of the writing is considerably increased.

The typewriting machine which has been hereinbefore described permits an increase the speed of writing owing to the fact that 25 the shifting of the lines is effected automatically and that the paper at the end of each line is automatically presented in proper position for the beginning of a new line of print. The machine is further distinguished by a light and easy touch as the spring has to be put under tension only once for every page and not for every fresh line.

I claim:—

1. An improved typewriting machine in 35 which the paper is held upon a revoluble cylindrical platen, comprising in combination a cylindrical platen which is arranged horizontally and perpendicularly to the operator, the axle of said cylindrical platen 40 consisting of two tubes telescoped the one

in the other, a spring inclosed in said tubes for driving the cylindrical platen in longitudinal direction and means for connecting said cylindrical platen with said axle so that it revolves with the axle while being free 45 to move upon the same in longitudinal direction, substantially as described and shown and for the purpose set forth.

2. In an improved typewriting machine having a cylindrical platen arranged horizontally and perpendicularly to the operator and having a radial notch, two telescoped tubes forming the axle of said cylinder and a ridge upon the outer tube which engages with said notch, substantially as described 55 and shown.

3. In an improved typewriting machine having a cylindrical platen arranged horizontally and perpendicularly to the operator, the device for the step-wise motion of 60 said platen at the end of each line consisting of an auxiliary shaft connected with the axle of said platen and oscillating at the end of every complete revolution of said platen, two gripping levers mounted upon 65 said auxiliary shaft, articulated hookshaped upper ends of said levers, a guide piece for the platen composed of uniformly spaced steps which bearing against said gripping levers lock the platen, and a support for the 70 platen fixed to the rear end of said guide piece, substantially as described and shown and for the purpose set forth.

In witness whereof I have hereunto set 75 my hand in the presence of two witnesses.

PAUL DE CARSALADE DU PONT.
